UNITED STATES PATENT OFFICE.

THOMAS B. ASHFORD, OF KINSTON, NORTH CAROLINA.

TROUSERS-PROTECTOR.

SPECIFICATION forming part of Letters Patent No. 448,599, dated March 17, 1891.

Application filed December 26, 1890. Serial No. 375,804. (No model.)

To all whom it may concern:

Be it known that I, THOMAS B. ASHFORD, a citizen of the United States, residing at Kinston, in the county of Lenoir and State of 5 North Carolina, have invented certain new and useful Improvements in Pantaloons-Protectors; and I do hereby declare that the following is a full, clear, and exact description of the same, reference being had to the annexed drawings, making a part of this specification, and to the letters of reference marked thereon.

Figure 1 of the drawings represents a sectional elevation of my improved protector, 15 showing it applied to the leg of a pair of pantaloons; Fig. 2, a detail plan view of the outer side of the protector; Fig. 3, a detail view of one of the combined brace and fasteners.

20 The present invention has for its object to provide a simple and effective device to be used as a protector for pantaloons, and also a simple means for attaching it thereto which will also serve as a brace or stay for the protector and thereby increase its durability and usefulness, which objects are attained by the device constructed as shown in the drawings, and hereinafter described and claimed.

In the accompanying drawings, A represents a portion of the leg of a pair of pantaloons shown in section and the position of the boot or shoe in relation thereto indicated by dotted lines.

35 The device which constitutes my invention, and which I term a "protector," is shown at B, and is formed of leather, rubber, or any preferred material and of any suitable size and shape best adapted to the purpose for which it is designed—viz., to protect the pantaloons where they rub against the heel of the 40 boot or shoe.

In the present instance I have shown the protector with a curved upper edge and a straight lower edge; but such shape may be 45 modified and other forms may be given to the protector without departing from the principle of my invention.

The protector has connected to it two or more braces or stays C, which are constructed 50 of metal and of sufficient length to extend around both sides of the protector to brace

the same and increase its wearing qualities. The braces or stays C serve a further purpose in that they are so constructed as to enable them to provide means for securing the protector to the pantaloons. 55

The braces or stays are constructed from a rectangular plate of suitable metal and have tongues a, one near each end, and a central tongue b, which tongues are cut or stamped out from the same metal from which the brace or stay is formed, as shown in Fig. 3. In securing the brace or stay to the protector the central tongue b is passed through the material thereof and the ends of the sheet-metal 65 plate bent around upon and against the opposite side, and the central tongue above described passed through the slot at one of the ends of the metal plate, which securely fastens the braces or stays to the protector. 70

The tongues a are bent out at right angles to the plane of the protector and passed through the turned-up portion c of the pantaloons and bent down against the same, as shown in Fig. 1, thus securely attaching the 75 protector in place upon the inner side of the pantaloons at that portion where it would come in contact with the heel of the boot or shoe.

The metal plates above described form a 80 binding for the protector as well as a stay and brace, with the additional advantage of a double fastener to secure it to the protector and to attach the protector to the pants.

The tongues of the fastener passing through 85 the turned-up portion or hem of the pants only, as shown at c, the tongues are entirely concealed from view while the protector materially improves the set of the leg of the pantaloons around the boot or shoe. 90

The protector herein described can be manufactured and placed upon the market at a comparatively small cost, and thereby bring it within the reach of those desiring such an article. 95

The means employed for rendering the protector strong and durable, and in addition thereto serving as the means of fastening it to the hem of the pantaloons, enables the article to be most economically produced, while 100 its value and usefulness are retained.

Having now fully described my invention,

what I claim as new, and desire to secure by Letters Patent, is—

A protector for pantaloons and means for securing it thereto, consisting of metal brace 5 or stay plates extending across the face and over the edges of the protector, said plate having a central tongue and two end tongues, the former for attaching the plate to the protector and the latter for attaching the pro-

tector to the pantaloons, substantially as and for the purpose specified.

In testimony that I claim the above I have hereunto subscribed my name in the presence of two witnesses.

THOMAS B. ASHFORD.
